CLAIM

The ornamental design for a workout level display indicator, as shown and described.

DESCRIPTION

FIG. 1 is a view of the subject design shown in the environment of a display panel for an exercise machine.

FIG. 2 shows an enlarged embodiment of the subject design in which color is indicated by cross-hatching; and,

FIG. 3 is an enlarged view of a second embodiment of the subject design in which color is indicated by cross-hatching. The subject design provides an ornamental design for a display that adds a visual dimension to heart rate interactive exercise. The design of the display incorporates both shapes and colors in a pleasing manner.

For convenience of illustration, the cross-hatching has been omitted from FIG. 1. The broken lines are shown for illustrative purposes only and form no part of the claimed design.
